TUBING AND CASING HEAD

Sheridan P. Tschappat, Tulsa, Okla.

Application April 3, 1937, Serial No. 134,797

3 Claims. (Cl. 285—22)

This invention relates to new and useful improvements in tubing and casing heads.

As is well known, it is the custom in oil well production practice to superimpose tubing and casing supports, whereby a plurality of concentric fluid conduits may be suspended in the well.

It is one object of this invention to provide improved means for connecting a casing support and a tubing support and having certain characteristics making for increased safety and greater ease of assembly, and also whereby the packing between the supports may be replaced without disturbing the well connections or having to lift the casing and its support.

15 An important object of the invention is to provide improved means for connecting supports together and including an elastic packing element which is so arranged as to be distorted by said means when the supports are secured 20 together.

Another object of the invention is to provide an improved connection between supports wherein a tubing support having a shoulder at its lower end is mounted on a flanged base member 25 from which casing is suspended, and a split ring, secured to the flanged base member, is adapted to overlie the flange on the upper end of the base member and to overhang the shoulder on the tubing support whereby vertical 30 placement of the support and member with relation to each other is prevented, the ring being split to facilitate application thereof so that a connection between said member and support may be readily made.

35 A further object of the invention is to provide improved means for connecting a tubing support and a vented base member having flanges at its upper and lower ends and having an internal shoulder for receiving said tubing support, wherein an elastic packing element is mounted at the joint between the members and a detachable ring is arranged to fasten the base member and support together, said ring also engaging the packing element so as to distort the same into 40 sealing position as the joint is made up.

45 A construction designed to carry out the invention will be hereinafter described, together with other features of the invention.

The invention will be more readily understood 50 from a reading of the following specification and by reference to the accompanying drawings, in which an example of the invention is shown, and wherein:

55 Figure 1 is an elevation of a base member having a tubing support superimposed thereon and

connected thereto in accordance with the invention.

Figure 2 is a plan view of the same.

Figure 3 is an enlarged, transverse, vertical, sectional view of the base member and support, 5

Figure 4 is a horizontal, cross-sectional view taken on the line 4—4 of Figure 1,

Figure 5 is a similar view taken on the line 5—5 of Figure 1,

Figure 6 is a plan view of the split retaining 10 ring showing the same before assembly,

Figure 7 is a view, partly in elevation and partly in section of another form of the invention, and

Figure 8 is a horizontal, cross-sectional view, 15 taken on the line 8—8 of Figure 7.

In the drawings, the letter A designates an annular flanged base member or casing head having a tubing support or head B superimposed thereupon.

20 The base member A includes a cylindrical body or shell 10 having an external annular flange 11 at its lower end, whereby the base member may be connected to a suitable support (not shown). The body has a vertical bore 12 25 and is provided with internally screw threaded radial outlets or ports 13 for receiving outlet pipes or conduits (not shown). The bore of the body is provided with internal screw-threads above and below the ports and is adapted to 30 receive the upper end of an outer well casing 14 which is screwed into the lower end thereof.

35 The upper end of the bore of the body is enlarged whereby an internal annular countersunk shoulder 15 is formed. This shoulder is adapted to receive the lower end of the tubing support B. An external annular connecting flange 16 is provided on the upper end of the body 10, whereby said body may be connected with the tubing support, as will be explained. External 40 vertical ribs 10' extend between the flanges on the body 10 strengthening the same.

The tubing support B may be of any suitable type, but for purposes of illustration a support is shown wherein an elongate tubular housing 17, 45 having an external annular flange 18 at its lower end, is adapted to rest on the shoulder 15 of the body 10. The housing has a cylindrical bore 19 having a slip bowl 20 formed therein, and the usual slips 21 are mounted in the bowl 50 and grip a well tubing 22 extending therethrough. Superimposed packing rings 23 are carried on the upper ends of the slips and are held in position thereon by a split gland nut 24 screw-threaded into the upper end of the bore 55

of the housing. The usual internally screw-threaded radial ports 25 are provided in the wall of the housing below the slips for receiving outlet pipes (not shown) for conducting fluid from the 5 bore of the housing. The lower end of the bore 19 is internally screw-threaded and receives the upper end of an inner well casing 26.

In providing a connection between the base member and support, an annular recess or offset 10 30 is provided in the upper end of the flange 18 on the tubing support. The provision of this offset in the flange forms a comparatively narrow annular shoulder 31 at the lower end of the tubing support. When the support is resting 15 on the shoulder 15 in the base member, as shown in Figure 3, the shoulder 31 is in horizontal alinement, or lies flush with, the upper surface of the flange 16 on the base member. An annular offset or recess 32 is formed in the enlarged portion 20 of the bore of the body 10 and extends complementary to the offset in the flange 18 on the tubing support, whereby, when said support is in position on the shoulder 15 in the base member, an annular groove 33 is formed between 25 said base member and support (Figure 3), and an annular elastic packing ring 34 is mounted in this groove. A split metal retaining ring 35 overlies the flange 16 on the base member and is secured thereto by bolts 36 passing through openings 37 in the retaining ring and openings 38 in the flange. The retaining ring is of such size 30 that its inner portion overhangs the shoulder 31 on the tubing support B and when the bolts 36 are tightened the ring engages the upper 35 surface of the flange 16 on the base member and the shoulder 31 thereby positively holding the tubing support in position on the shoulder 15. In moving the retaining ring to such position, the packing ring 34 within the groove 33 is 40 engaged by said ring and distorted into sealing position with the walls and bottom of the groove, providing a fluid-tight connection between the base member and tubing support.

For facilitating assembly, the retaining ring 45 35 is preferably of the sectional or split type, the sections thereof being connected by bolts 39 extending through openings 40 provided in upstanding ears 41 formed on the abutting ends of each section of the ring. Also, the opening 50 37' in the midportion of each section of the ring is internally screw-threaded to receive a stud bolt 36', which bolt is arranged to engage in a notch 38' provided in the outer periphery of the flange 16 on the base member. Therefore, 55 in positioning the retaining ring to surround the tubing support, the stud bolts are screwed into the openings 37' in each section and the sections moved into position. The bolts 36' enter the notches 38', thereby at once alining the bolt 60 openings in the flange 16 and the ring and affording a quickly made up connection, since the sections of the ring overhang the shoulder 31 on the support B and the stud bolts engaged in the notches 38' restrict upward displacement 65 of said ring and support. The sections are then connected together by the bolts 39 extending through the ears 41 and the bolts 36 applied to further secure the ring to the flange 16 on the base member.

70 The retaining ring is cut away adjacent the ears 41 to permit passage of tie down members 42 which extend upwardly from diametrically opposed lugs 43 depending from the flange

16 on the base member. These tie down members are used to prevent upward displacement of the base member, being secured to a suitable support (not shown).

It will be seen that the retaining ring provides a positive connection between the base member A and the tubing support B by engaging the shoulder 31 on the support to hold the same in position on the shoulder 15 in the upper end of the bore of the base member. 10 Also, the ring may be quickly and easily secured in holding position around the tubing support by sliding each section into engagement around the support and connecting the sections by the bolts 39. Similarly, the ring may be 15 readily removed from engagement with the tubing support to permit repacking at this point without disturbing the well connections or lifting the casing 14 or member 10. Since the stud bolts 36' are engaged in the notches 38' in such 20 assembly it will be seen that a positive connection may be quickly made, addition of the bolts 36 strengthening the connection, thus providing a rugged, easily made, positive connection between the base member and tubing support. 25

It is also to be noted that the packing ring 34 is distorted into sealing position by the retaining ring as the connection is made, thereby providing a fluid-tight joint simultaneously with the making up of a positive connection between the 30 base member and support.

In Figures 7 and 8, a slightly modified form of the invention is shown. The structure is exactly the same as that shown in Figures 1 to 6, with the exception that the inner well casing 26 35 is not screwed directly into the lower screw-threaded end of the bore 18 of the tubing support B. Instead, the upper end of the casing is connected in the lower end of the bore of a collar 50 which collar has its upper end externally threaded at 51, whereby it may be screwed into the bore 19 of the support B. The provision of the collar makes for easier assembly and also permits the inner casing to be of a smaller diameter than the diameter of the bore. 45

What I claim and desire to secure by Letters Patent is:

1. A casing head and tubing head assembly including, a casing head having an annular countersunk shoulder and an annular surrounding flange extending above said shoulder, a tubing head having an annular base engaging in said casing head and resting upon the shoulder thereof and forming with said flange an annular groove, an annular packing ring disposed within said groove for sealing the joint between said casing head and said base, and means to secure said tubing head within said casing head. 50

2. A casing head and tubing head assembly as set forth in claim 1 wherein the tubing head has a shoulder substantially flush with the top of the surrounding flange of the casing head so that the securing means rests rigidly on said last named shoulder and rigidly upon said flange and distorts and covers the packing ring. 60

3. A casing head and tubing as set forth in claim 1 wherein the securing means is made as a split ring for application when tie members are attached to the casing head, the flange of the casing head having notches, and fastening 70 depending from the said split ring and engaging in the notches of said flange.

SHERIDAN P. TSCHAPPAT.
